UNITED STATES PATENT OFFICE.

ALPHONSO MORRIS MELCHER, OF OSHKOSH, WISCONSIN, ASSIGNOR OF
ONE-HALF TO O. F. SCHUMANN, OF OSHKOSH, WISCONSIN.

FLUE-CLEANER.

SPECIFICATION forming part of Letters Patent No. 739,435, dated September 22, 1903.

Application filed February 19, 1903. Serial No. 144,065. (No model.)

To all whom it may concern:

Be it known that I, ALPHONSO MORRIS MELCHER, a citizen of the United States, residing at Oshkosh, in the county of Winnebago and State of Wisconsin, have invented new and useful Improvements in Flue-Cleaners; and I do hereby declare the following to be a full, clear, and exact description of the invention, such as will enable others skilled in the art to which it appertains to make and use the same.

The invention relates to improvements in flue-cleaners, and has for its object to provide a simple and inexpensive flue-cleaner adapted to be readily applied to a chimney and capable of adjustment to clamp the walls of chimneys having flues of different sizes, whereby the flue-cleaner is firmly held in position on a chimney.

A further object of the invention is to provide a flue-cleaner of this character which will be capable of convenient operation from the exterior of a chimney or flue to raise and lower a brush in the flue to remove the soot and other accumulations therefrom.

The invention also has for its object to provide a flue-cleaner in which the brush may be readily varied in size to adapt it to scrape properly the walls of chimneys having flues of various sizes and shapes.

The invention consists of the novel construction and arrangement of parts hereinabove described and shown, and particularly pointed out in the claims hereto appended.

In the drawings forming part of this specification, and in which like numerals of reference designate corresponding parts, Figure 1 is a side elevation of a flue-cleaner constructed in accordance with this invention and shown applied to a chimney, the latter being in section. Fig. 2 is a plan view of the supporting-bar and the pulley or sheave. Fig. 3 is a transverse sectional view on the line 3 of Fig. 4, illustrating the manner of mounting the pulley or sheave. Fig. 4 is a plan view of a portion of the brush. Fig. 5 is a vertical sectional view of the central portion of the same. Fig. 6 is a similar view showing a modified form of brush. Fig. 7 is a plan view of the same. Fig. 8 is a reverse plan view thereof. Fig. 9 is a plan view of the lower circular plate.

Referring to the drawings, 1 designates a horizontal supporting-bar designed to be arranged upon the top of a chimney 2 and provided at its ends with longitudinal slots 3 for the reception of bolts 4 for adjustably securing jaws 5 to the lower face of the bar. The jaws 5, which consist of L-shaped or angle plates, engage the inner face of the opposite walls of the chimney, as shown in Fig. 1, whereby the supporting-bar is firmly held in position.

The supporting-bar is provided with a central depending enlargement 6, and it has a vertical slot 7 therein, the side walls of the slot being provided with downwardly-tapered bearing-recesses 8 for the reception of journals 9 of a pulley or sheave 10, which is detachably mounted in the slot or opening 7. The pulley or sheave, which is formed integral with the journals, consists of a peripheral portion and a head or flange arranged at one edge of the peripheral portion.

The pulley or sheave receives the chain 11 or other suitable flexible connection, which is attached at its ends to a brush 12, consisting of a central clamp and a series of wires 13, designed to be arranged, as illustrated in Fig. 4 of the drawings, to provide a brush to conform to the configuration of the flue and adapted to be removed to permit other wires or brush material to be put in the clamp for changing the size or configuration of the brush. The clamp consists of a central vertical bolt or screw 14, a nut 15, and upper and lower circular plates 16 and 17, arranged on the screw between the head thereof and the nut and adapted to clamp the wires 13 or other material.

The lower plate 17, which is provided with depending lugs 18 for engaging the squared head of the screw 14, has a recess 19 adjacent to its central opening for the screw, and the wires are provided at their inner ends with depending projections 20 for engaging the recess 19 to prevent them from being pulled out of the clamp. The lower end is also provided at its upper engaging face with a series of notches to receive and space the wires or other brush material, the notches being preferably formed in an annular flange 21. The flange 21 is also provided with suitable

notches for the reception of inwardly-extending ends 22 and 23 of upper and lower bails 24 and 25, which constitute the means for connecting the ends of the chain with the 5 clamp of the brush. The inwardly-extending ends are arranged in suitable recesses of the flange 21. The upper bail or hanger is provided at the top with a U-shaped bend 26 to center the chain and is approximately U-10 shaped. The lower bail is approximately V-shaped, as shown.

In Figs. 6 to 8, inclusive, of the drawings is illustrated a modification of the invention in which the screw 27 has an enlarged head to 15 receive the lower plate 28 and is provided with lugs 29 for engaging the same. The upper plate 30, which is clamped by a nut 31, is provided with lugs 32 for engaging recesses of the enlarged portion of the screw. The 20 screw is provided at its ends with suitable eyes 33 and 34 to receive the ends of the chain.

The chain is arranged on the sheave or pulley in the slot or opening of the supporting-bar and its ends are connected with the 25 brush. It is of sufficient length to extend through the thimble of a stovepipe-opening to permit it to be operated from the exterior of the flue. One side of the chain is arranged between the wires or other brush material 30 and the brush is raised and lowered to scrape the accumulation from the walls of the flue.

What I claim is—

1. A flue-cleaner, comprising a horizontal supporting-bar provided at its ends with slots, 35 adjustable jaws provided with fastening devices operating in the slots, a pulley or sheave mounted on the bar, a brush and a flexible connection arranged on the pulley or sheave

and connected with the brush, substantially as described.

2. A flue-cleaner, comprising a bar provided with a central enlargement having an opening, and provided with open bearing-recesses in the walls of the opening, a pulley or sheave arranged in the opening, and provided with 45 journals fitted in the bearing-recesses, adjustable clamps, arranged on the lower face of the bar for engaging the walls of the flue, a flexible connection arranged on the sheave, and a brush connected with the flexible connection, substantially as described.

3. A flue-cleaner, comprising a brush composed of a bolt or screw having a nut, a lower plate interlocked with the bolt or screw and provided with notches at its upper face, an 55 upper plate, brush material clamped between the plates, and hoisting mechanism, connected with the brush, substantially as described.

4. A flue-cleaner comprising a brush composed of a screw, provided with a nut, a lower plate interlocked with the screw and provided at its upper face with notches and having an inner recess, an upper plate, and wires fitted in the notches and provided with projections for engaging the recess, said wires being detachable and interchangeable for varying the size and shape of the brush and means for raising and lowering the brush, substantially as described.

In testimony whereof I have hereto affixed 70 my signature in the presence of two witnesses.

ALPHONSO MORRIS MELCHER.
